UNITED STATES PATENT OFFICE

166,169

PAVEMENT REPAIRING MACHINE

Versal F. Baumgardner, Celina, Ohio

Application August 8, 1951, Serial No. 16,206

Term of patent 14 years

(Cl. D14—3)

To all whom it may concern:

Be it known that I, Versal F. Baumgardner, a citizen of the United States, residing at Celina, in the county of Mercer and State of Ohio, have invented a new, original, and ornamental Design for a Pavement Repairing Machine, of which the following is a specification, reference being had to the accompanying drawing, forming a part hereof, wherein:

I claim:

The ornamental design for a pavement repairing machine, substantially as shown.

VERSAL F. BAUMGARDNER.
